UNITED STATES PATENT OFFICE.

LOUISA POLSKY, OF STOCKTON, CALIFORNIA.

DESIGN FOR A HEATER AND FOOD-RECEPACLE.

No. 38,959.

Specification for Design.

Patented Dec. 24, 1907.

Application filed July 22, 1907. Serial No. 385,095. Term of patent 14 years.

To all whom it may concern:

Be it known that I, LOUISA POLSKY, a citizen of the United States, residing at Stockton, in the county of San Joaquin and State of California, have invented a new, original, and ornamental Design for a Heater and Food-Receptacle, of which the following is a specification, reference being had to the accompanying drawing, forming a part hereof.

In the drawing Figure 1 is a top plan view

showing my new design for heater and food receptacle. Fig. 2 is a side elevation of the same.

I claim;

The ornamental design for a heater and food receptacle, as shown.

LOUISA POLSKY.
